UNITED STATES PATENT OFFICE.

FRED A. WHITMORE, OF PHILADELPHIA, PENNSYLVANIA, ASSIGNOR TO CROMPTON & KNOWLES LOOM WORKS, A CORPORATION OF MASSACHUSETTS.

LOOM FOR WEAVING TUFTED OR CHENILLE FABRICS OR CARPETS.

1,102,835.

Specification of Letters Patent.

Patented July 7, 1914.

Application filed March 26, 1912. Serial No. 686,396.

To all whom it may concern:

Be it known that I, FRED A. WHITMORE, a citizen of the United States, residing at Philadelphia, in the county of Philadelphia and State of Pennsylvania, have invented certain new and useful Improvements in Looms for Weaving Tufted or Chenille Fabrics or Carpets, of which the following is a specification.

10 My invention relates to looms for weaving tufted or chenille fabrics or carpets, ordinarily termed chenille Axminster looms, and my invention relates to improvements in the class of looms referred to, and particularly 15 to improvements in the needle frame operating mechanism, and the chenille weft carrier mechanism, and the mechanism for operating the same.

The object of my invention is to improve 20 upon the ordinary construction of the needle frame operating mechanism, and the chenille weft carrier mechanism, and the mechanism for operating the same, in the class of looms referred to.

25 My invention consists in certain novel features of construction of my improvements as will be hereinafter fully described.

In the manufacture of chenille carpets, the chenille, which constitutes the pile of 30 the fabric, is prepared beforehand, and is placed in the fabric as weft, in parallel rows transversely of the fabric, in the shed of the binder warps. The chenille weft, which is also termed "fur," is sometimes carried into 35 the shed by shuttles, and sometimes, as in my present improvements, by a fur or chenille weft carrier, which consists of a tube suitably supported, and through which the chenille weft passes, and mechanism for 40 operating said tube automatically at predetermined intervals, after the shed for the fur or chenille is opened, and the binder or catcher warps for the chenille are in their upper position.

45 I have only shown in the drawings a detached portion of a chenille Axminster loom with my improvements combined therewith, sufficient to enable those skilled in the art to understand the construction and operation thereof.

Referring to the drawings:—Figure 1 is a front view of a portion of the left hand end of a chenille Axminster loom, and of the fur carrier mechanism, and operating 55 mechanism for the needle frame; the operat-

ing rack is partially shown in section. Fig. 2 is an end or side view of the fur carrier mechanism, shown at the upper part of Fig. 1, and looking in the direction of arrow *a*, same figure; for the sake of clearness the 60 bearings and stands are not shown in this figure. Fig. 3 shows the operating disk shown at the left in Fig. 2, detached, and in a different position. Fig. 4 is a plan view of the parts shown in Fig. 2, looking in the 65 direction of arrow *b*, same figure, and, Fig. 5 is a sectional end view, on line 5, 5, Fig. 1, looking in the direction of arrow *a*, same figure.

In the accompanying drawings, 1 is the 70 loom side or end frame, 2 is the lay, see Fig. 2, and 3 the reed thereon, preferably open at its upper end.

4 is the breast beam plate over which the 75 woven fabric 5 passes.

6 are the binder warps, which are raised and lowered by two harnesses, not shown, in the usual way. 7 are the catcher warps which bind the chenille weft, and which, from the fell of the fabric, pass through 80 eyes 8' at the lower ends of vertically extending needles 8, and then upwardly to catcher warp spools, not shown, in the usual way.

9 is the needle frame, which has upwardly 85 extending projections 10 at each end, see Fig. 1, which enter recesses in the guide frame 10', secured to the loom side. The needle frame 9 has an up and down movement communicated thereto by mechanism 90 on the loom, to be hereinafter described.

11 is the driving shaft, and 12 is the crank shaft of the loom.

All of the above mentioned parts may be of any well known construction in the class 95 of looms referred to.

I will now describe my improvements in the needle frame operating mechanism, and the fur or chenille weft carrier mechanism, and mechanism for operating the same.

The projection 10 at each end of the needle frame 9, has ears or lugs 10' thereon, see Fig. 1, to which is pivotally connected the upper end of a downwardly extending connector 13. The lower end of said connector 13 is mounted on the wrist of the crank 14' on the crank shaft 14, which is suitably mounted in bearings at the lower portion of the loom side 1. The crank shaft 14 has a plurality of cranks 14' thereon, for oper- 110

ating the needle frame, and has the pivotally mounted rigid connectors 13, extending between said cranks and the needle frame. The crank shaft 14 receives a revolving movement at predetermined intervals, by a mutilated pinion 15, fast on the crank shaft 14. The mutilated pinion 15 meshes with and is driven by a mutilated gear 16 fast on a shaft 17. A spur gear 18, which in this instance is rigidly connected with the mutilated gear 16, meshes with and is driven by a pinion 19 fast on the crank shaft 12 of the loom.

Adjustably connected to the gear 18 on the shaft 17 is in this instance a cam 20, which is adapted to engage with its periphery a roll 21 mounted on a stud 22' on a horizontally extending lever 22, which is pivotally mounted at its inner end on a stud 22' on a bracket on the frame 1, see Fig. 5. The outer end of the lever 22 is pivotally connected to the lower end of an upwardly extending connector 23, see Figs. 1 and 5. The upper end of the connector 23 is pivotally connected to a stud 24 on a slide 25, see Figs. 1 and 2, which slide is suitably guided on the guide frame 10^a.

The revolution of the crank shaft 12, through intermediate connections, communicates an up and down movement to the slide 25, and also, through intermediate connections, communicates a rotary movement to the crank shaft 14 and the crank 14' thereon, and when the needle frame 9 is in its upper position, as shown in Fig. 1, the slide 25 is in position to start the operation of the fur carrier, to be hereinafter described.

26 is the fur or chenille carrier, see Fig. 1, having extending therefrom toward the breast beam, a tube 26', through which the chenille weft, not shown, passes in the usual way. The fur carrier 26 is mounted on two rods 27 and 28, which extend transversely across the loom in the direction of its width, and has a sliding movement on said rods, in the usual way. An endless cord 29 is attached to the fur carrier 26, and passes over pulleys 30 and 31, see Fig. 4, and around a drum 32 at one end of the loom, which drum has grooves in its periphery, and around a grooved wheel or pulley at the other end of the loom, not shown, in the usual way. The drum 32 is rotated, first in one direction, and then in the other direction, through a crank and rack operating mechanism.

60 The drum 32 is mounted on a shaft 33, which has a pinion thereon, not shown, which meshes with and is driven by a gear 34, see Fig. 4, mounted on a shaft 35, which is suitably mounted in bearings, and in the rack guide 36, see Fig. 1. The shaft 35 has a pinion 37 mounted thereon, see Fig.

1, which meshes with and is driven by a rack 38, which is suitably guided in the rack guide 36. The rack 38 is provided with a stud 39, see Fig. 4, to which is pivotally connected one end of a horizontal connector 40; the other end of said connector 40 is connected to the wrist of the crank 41' of a crank shaft 41, which is suitably mounted in bearings 42, 43, and 44, see Fig. 4.

A disk 45 has its hub 45' secured on the crank shaft 41. The hub 45' of the disk 45 has lugs or ears 45'' thereon, see Fig. 4, on which are pivotally mounted one end of the locking fingers 46, which are guidingly held at their ends by the projection 45''' on the disk 45. Helically coiled expansion springs 47, inclosed in bosses 47' on the disk 45, (only one spring is shown in Fig. 4,) are adapted to yieldingly move the fingers 46 toward a second disk 48, when said fingers are released, as will be hereinafter described. The disk 48 has its hub 48' loosely mounted on the shaft 41, and said hub 48' is carried in a bearing 44, and has fast thereon, on its outer end, the hub 49' of a gear 49, which gear meshes with and is constantly driven by a pinion 50 on a shaft 51. The shaft 51 carries a gear 52, which meshes with and is driven by a pinion 53 on the driving shaft 11.

The slide 25, above referred to, has a boss 54' thereon, see Fig. 2, which carries a pin 54, adapted to engage and move upwardly one arm of a horizontally extending lever 55, see Fig. 4. The other arm of the lever 55 has pivotally connected to its end the upper end of a connector 56, see Fig. 2. The lower end of the connector 56 is pivotally connected to one arm of an angle lever 57, which has its hub pivotally mounted on a stud 57'. The other arm of said angle lever 57 has pivotally connected thereto one end of a horizontally extending connector 58; the other end of said connector 58 is pivotally connected to a downwardly extending arm of a lever 59, which has its hub 59' centrally mounted on a stud 60, see Fig. 2. The upwardly extending arm of the lever 59 has pivotally attached thereto one end of an arm or lever 61, which extends toward and above the disk 48. The arm or lever 61 has a hook projection 61' thereon, which is adapted to engage with the upper engaging end of a cam lever 62, which has its lower end pivotally mounted on a stud 63, see Figs. 2 and 3. A helically coiled contraction spring 64, attached at one end to the lever 61, and at its other end to the cam lever 62, acts to yieldingly hold the hook arm 61 in engagement with the end of the lever 62.

The lower end of the lever 59 has pivotally connected thereto one end of a connector 65; the other end of said connector 65 is pivotally connected to the lower end 130

of an arm 66, which has its hub 66' pivotally mounted on a stud 67, see Figs. 2 and 3. The arm 66 has pivotally mounted thereon one end of an arm or lever 68, which 5 has a hook projection 68' thereon, adapted to engage with the end of a downwardly extending lever 69, which is pivotally mounted on a stud 70, see Figs. 2 and 3. A helically coiled contraction spring 71 is attached at one end to the lever 68, and at its other end to the cam lever 69, and acts to hold the hook arm 68 in engagement with the end of the lever 69.

Through the upward movement of the 15 slide 25, and the intermediate connections, above described, to the levers 62 and 69, said levers 62 and 69 are moved away from the disks 45 and 48, as shown in Fig. 3, and are caused to be disconnected from, and 20 to release the fingers 46, pivotally mounted on the disk 45, as above described, to allow said fingers, through the action of the springs 47, to be moved toward the disk 48. The disk 48 has an inwardly turned rim, 25 which is provided with notches 48'; (one of these notches is shown in Fig. 1), which notches are adapted to engage the fingers 46, and through said fingers, cause the revolution of the disk 48 fast on the crank 30 shaft 41, to operate said crank shaft 41 and the crank 41', and through the connector 40, move the rack 38 to operate the cord drum 32, and the fur carrier 36. On the continued revolution of the disk 48, in the 35 direction indicated by the arrow in Fig. 3, the fingers 46 engage the ends of the hooked arms 61 and 68, to operate said arms, and move them out of engagement with the ends of the levers 62 and 69, to 40 allow said levers 62 and 69 to move back into the position shown in Fig. 2. The levers 62 and 69 have the cam-shaped or inclined edges 62', (only one is shown in Fig. 1), which, in engaging the fingers 46, will move

them out of engagement with the notches 48' 45 on the disk 48, to stop the rotary motion of the disk 45 and the revolution of the crank 41' on the crank shaft 41, which in this instance has finished one-half of its revolution, and the fur carrier 26 has been 50 moved one way across the loom.

To stop the motion of the crank 41' and lock it at each end of its rotary travel, a cam 72 is provided, which in this instance is mounted on the end of the crank shaft 41, 55 and is shown by broken lines in Fig. 2. The cam 72 is adapted to engage a roll 73 on a lever 74, said lever 74 has its lower end pivotally mounted on the loom side at 74', see Fig. 2. A helically coiled contraction 60 spring 76 acts to hold the roll 73 against the cam 72, to hold the crank 41', when it is in its end position, as shown in Fig. 3.

It will be understood that the details of construction of my improvements may be 65 varied if desired.

Having thus described my invention, what I claim as new and desire to secure by Letters Patent is:—

In a loom of the type referred to, a che- 70 nille weft carrier, a guide for the same, a flexible connection from the carrier to a drum, and said drum, means for operating said drum, said means including a crank shaft, a crank thereon, gearing connected to 75 the drum, and a connection from said crank to said gearing, means to operate said crank shaft, said means including a member fast on said shaft, and a driven member loose on said shaft, and connections intermediate 80 said members, to cause them to move in unison to rotate said crank shaft and said drum, at predetermined times.

FRED A. WHITMORE.
